Primary Examiner — Janice Hallmark(74) *Attorney, Agent, or Firm* — Seyfarth Shaw LLP(57) **CLAIM**

The ornamental design for a fan with cage, as shown and described.

DESCRIPTION

FIG. 1 is a perspective view of a fan with cage in accordance with my design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left elevation view thereof; and,

FIG. 7 is a right elevation view thereof.

The broken lines in the drawings illustrate portions of a fan that form no part of the claimed design.
